(57) **CLAIM**

The ornamental design for a container with surface indicia, as shown and described.

DESCRIPTION

FIG. 1 is a perspective view of a container with surface indicia, embodying our new design;

FIG. 2 is a front view of the container with surface indicia of FIG. 1.

FIG. 3 is a back elevational view of the container with surface indicia of FIG. 1;

FIG. 4 is a first side elevational view of the container with surface indicia of FIG. 1;

FIG. 5 is a second side elevational view of the container with surface indicia of FIG. 1;

FIG. 6 is a top view of the container with surface indicia of FIG. 1; and,

FIG. 7 is a bottom view of the container with surface indicia of FIG. 1.

The broken lines shown in the drawings are for illustrative purposes only and form no part of the claimed design.
